UNITED STATES PATENT OFFICE.

HARRY B. SAXTON, OF PORTLAND, OREGON.

CAP AND THE LIKE.

Application filed June 21, 1923. Serial No. 646,907.

To all whom it may concern:

Be it known that I, HARRY B. SAXTON, a citizen of Russia (having declared his intentions to become a citizen of the United States and obtained his first papers), and a resident of Portland, county of Multnomah, State of Oregon, have invented a certain new and useful Improvement in Caps and the like, of which the following is a specification.

This invention relates to caps, and the like, and has to do with the providing of means by which the interior of the hat may be ventilated and thus to permit a current of air to pass through the cap and thus keep the wearer's head cool.

One of the main objects of my invention is to provide a ventilating arrangement for a cap and the like, which cannot be inadvertently closed by the folds of the cap covering the passageway for the air. This ventilating arrangement will also permit the sweat band of the cap to conform uniformly to the wearer's head which adapts the cap to be worn comfortably.

A further and more specific object is to construct a cap or the like, which is perfectly ventilated and is comfortable to the wearer, and which does not require any change in the present standard form of cap nor will it necessitate the cutting away of any portion of the cap. That is, the ventilating means is inserted in the standard form of cap and does not require that the visor like projection be cut away to receive the same or that the lining or other standard part be left off so that the same may be adapted to attain the objects before mentioned.

I attain these and other objects by providing a piece of coarse woven resilient fabric, preferably a piece of metallic screen, which is sewn between the visor like projection of the cap and the sweat band. This permits the air to pass between these portions and provides a resilient support for the sweat band. I preferably arrange the woven resilient material, with the strands extending diagonally with the visor-like projection and the sweat band so that the compression of the resilient material when the cap is worn, and the front of the cap conforms to the shape of the forehead will not result in the flexing of any of the strands themselves but will only cause them to give angularly with each other.

I illustrate these and other objects in the accompanying drawings, in which:

Fig. 1 is a perspective view of a cap with my ventilating and cushioning improvement 60 in position, the arrows in this drawing showing the direction of the air passing through the cap when the same is on the wearer's head.

Fig. 2 is a fragmentary sectional view, 65 rather diagrammatic which shows the relation of the parts to each other and the arrows in this figure show the direction of the passage of air into the cap.

Fig. 3 is a fragmentary plan view of my 70 invention as adapted to a hat and the arrows in this figure similarly show the passage of the air into the crown of the hat.

Fig. 4 is a fragmentary sectional view through the hat and shows the relation of 75 the ventilating means therein.

Figs. 5 and 6 are fragmentary diagrammatic views of details of construction.

Fig. 7 is a perspective view of a cap which shows a slightly different form of ventilat- 80 ing and cushioning means.

Fig. 8 is a diagrammatic fragmentary section of a cap and arrows are provided to indicate the movement of air through the ventilating means into the cap. 85

Figs. 9 and 10 are detailed views showing how the ventilating section is fastened to the sweat band of the cap.

My improved ventilating and cushioning means is adapted for use with any standard 90 cap, as, *a*, or hat, as *b*. I provide a section of screen mesh as *c* which I sew to the visor *d* or brim *d'* on its inner edge as *e* or *e'* where it is also sewn to the crown *i* or *i'*. It is not necessary to redesign the cap or to 95 cut away any portion thereof. The other end of the ventilating screen *c* is fastened to the lower edge of the sweat band *f*. Thus the sweat band is spaced from the inner edge of the visor, and as this mesh is more or 100 less resilient and the sweat band is flexible my device permits the cap to be fitted to any peculiarities of the wearer's head without undue binding or irritation.

In Figs. 1 to 6, inclusive, I have shown the 105 ventilating screen *c* as bent double upon itself and thus the adaptiveness of my cap to the wearer's head is not dependent entirely upon the natural resiliency of the screen mesh.

Since, in putting the cap on the head, the ventilating insert must be bent to form the 110

front of the cap to the head of the wearer, it is obvious that in such bending the strands composing the ventilating insert must work from each way more or less so as to become relatively rearranged to the form which is given to the ventilating insert as a whole. Thus when the ventilating insert is made of a substantial flat piece of wire cloth, more or less resistance will be offered by the insert to its conformation to the head. I therefore prefer to make said ventilating insert of a folded piece of resilient wire cloth arranged like an inverted V in cross section. As a consequence the two members of the V will tend to separate at their extremities due to their resiliency and in that way provide a ventilation space; at the same time they will readily yield to pressure bringing them closer together when the cap is put on the head, and hence tend to render the cap more comfortable.

In Figs. 7 to 10, inclusive, I have shown a piece of the ventilating screen as *g*, which is similarly placed between the visor *d* and the sweat band *f*, but differs in that the screen lies all in one plane and the adaptiveness of the ventilating screen results entirely from the resiliency of the screen mesh. I preferably place this screen mesh *g* so that it will be arranged diagonally between the sweat band and the visor, that is, the resultant compression between these two parts will not flex any of the strands in the wire mesh upon itself. But as the longitudinal and transverse strands are both at an angle to this forward or compressive stress, this will result in the strands of wire being moved relatively with each other. It will not necessitate the wire being distorted as a whole but will cause only the strands to move angularly with each other. This not only results in greater resiliency and more comfort to the wearer but also results in longer life of the mesh screen in that the constant flexing of the strands would eventually cause them to be fractured.

As will be noted in both types of caps, it is possible to have a lined cap, the lining being shown as *h*. Either form of ventilating screen will function at all times even in a cap because the folds or material can never close the apertures so as to prevent the air from coming into the cap, because the sweat band *f* of the cap lies along the wearer's forehead and causes the same to stand in an upright position at all times, and will always remain in that position because of its rigidity. As is well known the visor is made with a stiff piece of cardboard *j* or similar material and this will cause it to stand out horizontally and will be held spaced because of the resiliency of the screen mesh.

I provide a flap *k* which normally is held by the lining of the cap but if too much air

enters the cap the flap may be placed over the screen section to prevent air from entering, or to materially decrease the same.

I claim:

1. In a cap, and the like, a crown provided at its bottom edge with a visor-like projection, a sweat band secured within the crown, spaced at the front from said projection, a ventilating strip of coarse woven resilient material covering said space, and having its edges secured to the adjacent portions of the visor-like projection and the sweat band, the strip being so arranged that its strands extend diagonally with said edges. 70

2. In a cap, and the like, a crown provided at its bottom edge with a visor-like projection, a sweat band secured within the crown, spaced at the front from said projection, a ventilating strip of metallic screen covering said space, and having its edges secured to the adjacent portions of the visor-like projection and the sweat band, the strip being so arranged that its strands extend diagonally with said edges. 75

3. In a cap, and the like, a crown provided at its bottom edge with a visor-like projection, a sweat band secured within the crown, spaced at the front from said projection, a folded ventilating strip of coarse woven resilient material covering said space, and having its edges secured to the adjacent portions of the visor-like projection and the sweat band, the strip being so arranged that its strands extend diagonally with said edges, the fold of said strip projecting upwardly into said space. 90

4. In a cap, and the like, a crown provided at its bottom edge with a visor-like projection, a sweat band secured within the crown, spaced at the front from said projection, a folded ventilating strip of coarse woven resilient material covering said space, and having its edges secured to the adjacent portions of the visor-like projection and the sweat band, the strip being so arranged that its strands extend diagonally with said edges the fold of said strip projecting upwardly into said space, a piece of closer-mesh fabric fastened along one edge of said ventilating strip and adapted to be drawn over the latter, thereby to prevent, more or less, the passage of air through said ventilating strip. 100

5. In a cap, and the like, a crown provided at its bottom edge with a visor-like projection, a sweat band secured within the crown, spaced at the front from said projection, a ventilating strip of coarse woven resilient material covering said space, and having its edges secured to the adjacent portions of the visor-like projection and the sweat band, a piece of closer-mesh fabric fastened along one edge of said ventilating strip and adapted to be drawn over the latter, thereby to 110

prevent, more or less, the passage of air through said ventilating strip.

6. In a cap or the like, a crown provided at its bottom edge with a visor-like projection and sweat band secured within the crown of the cap and spaced at the front of the cap from said visor, a folded resilient strip of wire cloth arranged like an inverted **V** in cross section covering said space, the edges of said strip being secured in place with relation to said visor and the sweat band.

7. In a cap or the like, a crown provided at its bottom edge with a visor-like projection and sweat band secured within the crown of the cap and spaced at the front of the cap from said visor, a folded resilient ventilating strip arranged like an inverted **V** in cross section covering said space, the edges of said strip being secured in place with relation to said visor and the sweat band.

HARRY B. SAXTON.
